DESIGN FOR A BOTTLE CAP REMOVER

Rudolph Block, Washington, D. C., assignor of one-half to Marie A. Ahern, Washington, D. C.

Application August 22, 1944, Serial No. 114,969

Term of patent 3½ years

(Cl. D44—29)

To all whom it may concern:

Be it known that I, Rudolph Block, a citizen of the United States of America and a resident of the city of Washington, District of Columbia, have invented a new, original, and ornamental Design for a Bottle Cap Remover, of which the following is a specification, reference being had to the accompanying drawing, forming a part thereof.

In the drawing,

Fig. 2 is a side view thereof; and

Fig. 3 is a cross-sectional view, taken on the line 3—3, Fig. 1.

I claim:

The ornamental design for a bottle cap remover, substantially as shown.

RUDOLPH BLOCK.
